New York

Filed Mar. 18, 1966, Ser. No. 1,538

Term of patent 14 years

(Cl. D64—11)

The figure on the drawing is a front perspective view of a key button for office machines showing my new design.

The essential features of my design reside in the solid line markings on the key button.

I claim:

The ornamental design for a key button for office machines, substantially as shown and described.
